ICE-CREAM LIFT

Harman B. Woerner and David C. Russell,
Terre Haute, Ind.Application December 30, 1931
Serial No. 583,886

5 Claims. (Cl. 220—93)

This invention relates to means for raising the lower remaining portion of ice cream from the lower part of a can to the upper part after the upper part has been served in order that the cream may be readily available without having to run one's arm down inside the can to the bottom thereof.

The invention also has advantages in that the bottom plate has removable lifting straps to permit stacking of the plates when not in use, and in the forming of the upper strap ends to be pressed outwardly against the can sides as they are being lifted so as to insure that the ends will spring over the top edge of the can when sufficiently lifted.

A further advantage of the invention is in the particular form of lifting jack so as to secure light weight with positive action and to have a base adapted to engage the can edge whereby a strap engaging member may be lowered quickly below the base to within the can to engage with the lifting strap and then pulled back upwardly to lift the straps.

These and other objects and advantages will become apparent in the following description of one form of the invention as illustrated by the accompanying drawing, in which

Fig. 1 is a side elevation of a structure embodying our invention as applied to an ice-cream can shown in transverse section;

Fig. 2, a fragmentary end elevation;

Fig. 3, a top plan view; and

Fig. 4, a detail in vertical transverse section through a can illustrating the manner of engagement of the lifting straps with the can top edge.

Like characters of reference indicate like parts throughout the several views in the drawing.

We form a circular plate 10 to have a diameter which will permit it to be moved freely up and down within the ice-cream can 11 but with slight clearance therebetween. Notches are cut in the plate edge on diametrically opposed sides so that lifting straps 12 and 13 can extend from under the plate and up through these notches without interfering with the movement of the plate in the can.

Each strap 12 and 13 has a lower end bent at right angles to a major portion thereof to extend horizontally inwardly under the plate 10 to pass removably through a loop 14 which is formed by punching a section of the plate downwardly. The major portion of each strap extends vertically upward through the respective notch in the plate and terminates with an upper end which is formed by bending a portion of the

strap inwardly and downwardly and then around upwardly and over outwardly toward the side of the can to form a shoulder 15 at the inner lower bend, and finally bending around downwardly from the end to form a downturned hook 16, the outer end of which extends slightly beyond the plane of the main vertical part of the strap.

The straps 12 and 13 and plate 10 may be kept separately until the can 11 is to be used, when the straps are then attached to the plate 10 by inserting the lower ends under the plate through the loops 14. The plate 10 with the straps thus attached is lowered into the empty can and pushed on down to rest on the bottom

of the can. The upper ends of the straps are sprung inwardly sufficiently to cause the upper hooks 16 to pass inside the can without engaging the top edge. Ice-cream is then poured into the can to fill it and hardened. The top ends of the straps 12 and 13 terminate at about half way up the can. When ice-cream has been dipped out of the can sufficient to uncover the upper ends of the straps 12 and 13, the person dispensing the ice-cream has reached down into the can about as far as is convenient and as is possible without rubbing his coat sleeve against the inside of the can.

It is to be understood that the can to which reference is herein made is the usual elongated can employed by creameries to harden and deliver cream in. When the strap ends are uncovered, the ends are then available to be engaged in order to pull up the plate 10 and thereby lift the remaining ice-cream to the upper part of the can. Since the cream is frozen

in the can it requires some little pull on the plate to break the cream loose from the can wall.

In order to pull up the plate 10 and lift the cream thereabove, we provide a special lifting mechanism which will now be described. We take two pieces 18 and 19 of strap metal and tie them together in spaced apart parallel relation by bands 20 and 21 to slidably carry a bar 22 therebetween, the lower ends of the pieces 18 and 19 are spread apart and are each provided with outturned toes 23 and 24 to rest on the top edge of the can 11 and with a downturned toe 25 between the other toes to extend downwardly within the can so as to retain the ends on the can edge.

The strap piece 18 is bent by its portion above the band 20 outwardly at an angle to the bar 22 and pivotally carries on this bent out portion an operating handle 26 which is here shown as a U-shaped band of metal having its open ends

straddling the bent portion. Between the open ends of the handle 26, we rockably secure a pawl 27 with an upper head having a tooth like member directed toward the bar 22 and a leg hanging below the pivot line of connection with the handle. A spring 28 having one end held against the piece 18 bears by its other end against the lower leg of the pawl 27 normally to rock the pawl head toward said bar 22. The piece 19 extends up along back of the bar 22 for a distance as a support against which the bar 22 may bear when pressed against by the pawl. The bar 22 is perforated substantially throughout its length by holes 29 into which the toothed 15 end of the head of the pawl 27 may engage.

A bracket 30 extends from the piece 19 to rockably carry a dog 31 which has an upper toothed end directed toward the bar 22 through an opening provided therefor in the piece 19. 20 The dog 31 also has a lower depending end which is normally pushed out away from the piece 19 by a spring 32 bearing against the piece 19 so that the toothed end is normally pressed against the bar 22. The bar 22 has a sufficient length to permit it in its lowermost position to extend down into the can 11 to permit a channel bar 33 fixed on the lower bar end to be slipped by its ends to under the shoulders 15 on the straps 12 and 13.

30 The handle 26 is pushed down to lift the pawl 27 so that the upper pawl end will slide over the bar 22 to drop into a hole 29 and thereby lift the bar 22 during the remainder of the upward travel of the pawl. The dog 31 drops into the 35 holes 29 as they are carried therewith so that, when the handle 26 is lifted to drop the pawl 27 to a lower hole 29, the dog 31 dropping into a hole 29, will hold the bar 22 against dropping, and by again pushing down on the handle 26 40 the pawl 27 will lift the bar 22 again.

When the bar 22 has been sufficiently lifted by working the handle 26 up and down, the strap ends 16 will spring over the top edge of the can edge and thereby hold up the plate 10. The 45 lower ends of the pawl 27 and dog 31 may then be pressed in to carry the upper ends thereof away from the bar 22 to release the bar and permit the lower channel bar 33 to be turned around from under the shoulders 15 and allow the entire lifting mechanism to be removed from over the can. By having the channel bar 33 engage the straps 12 and 13 under the shoulders 15, a rocking action on the ends of the strap is set up tending to force the hooks 16 against 50 the wall of the can and thereby spring the hooks over the can top edge when carried that far.

While we have here shown and described our invention in the one form as now best known to us, it is obvious that structural changes may be 55 made without departing from the spirit of the invention, and we therefore do not desire to be limited to that precise form beyond the limitations as may be imposed by the following claims.

We claim:

1. For lifting ice-cream in a can, a plate adapted to slidably fit within the can, and a pair of straps adapted to engage said plate, each of said straps having an upper hooked end and a lower inturned end adapted to removably engage under said plate a bar pulling on the straps, said bar extending from one strap to the other and means for detachably securing the bar-ends to their adjacent straps. 80

2. For lifting ice-cream in a can, a plate adapted to slidably fit within the can, and a pair of straps adapted to engage said plate, each of said straps having an upper hooked end and a lower inturned end adapted to removably engage under said plate, the upper hooked end of each strap having a shoulder therebelow, and a bar having a lower transverse member adapted to engage by its ends under said shoulders as a means for pulling on said straps. 90

3. For lifting ice-cream in a can, a plate adapted to slidably fit within the can, and a pair of straps adapted to engage said plate, each of said straps having an upper hooked end and a lower inturned end adapted to removably engage under said plate, the upper hooked end of each strap having a shoulder therebelow, and a bar having a lower transverse member adapted to engage by its ends under said shoulders as a means for pulling on said straps, said shoulders being spaced inwardly from the straps whereby pressure upwardly against the shoulders will tend to spring the hooked ends against the can wall. 100

4. For lifting ice-cream in a can, a plate adapted to slidably fit within the can, and a pair of straps adapted to engage said plate, each of said straps having an upper hooked end and a lower inturned end adapted to removably engage under said plate, the upper hooked end of each strap having a shoulder therebelow, and a bar having a lower transverse member adapted to engage by its ends under said shoulders as a means for pulling on said straps, and jack means engaging said bar. 110

5. For lifting ice-cream in a can, a plate adapted to slidably fit within the can, and a pair of straps adapted to engage said plate, each of said straps having an upper hooked end and a lower inturned end adapted to removably engage under said plate, the upper hooked end of each strap having a shoulder therebelow, and a bar having a lower transverse member adapted to engage by its ends under said shoulders as a means for pulling on said straps, said shoulders being spaced inwardly from the straps whereby pressure upwardly against the shoulders will tend to spring the hooked ends against the can wall, and means for pulling up on said bar. 125
